UNITED STATES PATENT OFFICE.

ADELMER MARCUS BATES, OF CHICAGO, ILLINOIS, ASSIGNOR TO BATES VALVE BAG COMPANY, OF CHICAGO, ILLINOIS, A CORPORATION OF WEST VIRGINIA.

PROCESS OF WIRE-TYING BAGS.

1,131,311.

Specification of Letters Patent.

Patented Mar. 9, 1915.

Application filed December 13, 1911. Serial No. 685,536.

To all whom it may concern:

Be it known that I, ADELMER MARCUS BATES, a citizen of the United States, residing at Chicago, in the county of Cook and State of Illinois, have invented a certain new and useful Improvement in the Process of Wire-Tying Bags, of which the following is a specification.

My invention relates to wire-tying closures for receptacles and the like, and is particularly applicable to the tying of yielding receptacles such as bags, to form the closures thereof.

The process is illustrated or its various steps pointed out diagrammatically in the accompanying drawings, where it is shown as applied to closing the open mouth of an empty bag.

Figure 1 is a plan view with the bag holding apparatus open; Fig. 2 is a similar view with parts shown in section and dotted lines and the bag inclosed; Fig. 3 is a similar view with the welding completed; Fig. 4 is a side elevation illustrating an early stage of the operation; Fig. 5, a part elevation and part cross section showing the ring completed; Fig. 6, a plan view of the parts illustrating the beginning of the tightening operation; Fig. 7, a plan view of the parts where the process has been completely carried out.

Like parts are indicated by like letters throughout the several figures.

A is a frame piece on which a reciprocating rod B is mounted. This rod has a hook C at one end adapted to engage the ring D and when reciprocated as illustrated in Fig. 6, to tighten the ring; and when turned on its axis, to twist the ring as at E and form the unlocking key F.

G is a bag and H a support against which it may be drawn during the tightening process.

J, J' are pivoted arms, one carrying the movable electrode J' inwardly forced by the spring J² and connected by the conductor J³ with the generator J⁴.

K is a half ring at the outer end of which are the arms K¹, K², the latter having the electrode K³ connected by the conductor K⁴ with the generator J⁴.

L is a circuit making and breaking device which may be included either in the conductor J⁴ or K⁴.

M is a section of wire adapted, when its ends are brought around and overlapped and welded, to form the ring D. The half ring K and the arms K¹ K² together, when folded in the position shown in Figs. 2 to 5 inclusive, form the downwardly depending forming ring placed so that as the wire M is carried forward and bent around it by the arms J, J', it will fall into the position indicated in the drawings about the forming ring and just above the bottom thereof. Driving means not shown are provided which are so arranged that one arm J will move in advance of the other, and they are suitably grooved to retain the wire, so that when the parts are folded together as indicated in Fig. 2, the ends of the wire are overlapped one on the other. The electric current is then turned on and as the welding softens the metal, the two overlapped portions are pressed together by the spring J² so that they come eventually into practically the position indicated in Fig. 3. Thus a completed inclosing ring is formed with the least possible amount of wire, and with the object to be tied inclosed thereby. The inclosing ring has no projecting parts, and requires for its formation no rotating or violently moving parts. The inclosing ring, however, is a little larger than the object to be tied, but much smaller than it would be if it were separately made large enough to slip over the end of the bag. The inclosing ring is now released and dropped down onto the object, in this case a folded bag. The hook C on the rod B has during the operation been within the inclosing ring, and it is now retracted in any desired manner, the bag being supported against the part H, which is itself supported by a frame not shown, whereupon the inclosing ring is tightened on the bag. To make the closure permanently tight, the rod is rotated so as to twist and form a loop in the inclosing ring, as shown in Fig. 7. This loop has no projecting sharp ends, and may be flattened down against the bag and can be used to untwist and thus loosen the inclosing ring and free the bag.

The drawings are of course diagrammatic. They are intended to show or suggest a means or apparatus by which the method or process can be carried out, but obviously the

process can be carried out by hand except as to the matter of welding and it could be carried out by some other and greatly varying structures. The ring, of course, need not in every case be overlapped, but for ordinary bags, and it is for such use that I have illustrated my invention, such fine wire is used that it is important, if not necessary, to overlap it.

10 The term welding is here meant to include any means for attaching the ends together where they are not twisted or tied or where heat is employed, and it specifically includes that method wherein an electric current is employed.

15 The inclosed ring is formed, broadly speaking, about the object to be tied, and in this particular case, about the forming ring which surrounds or holds the object to be tied. The forming ring, or some hand tool or substitute therefor, is necessary to enable the welding or heating process for finishing the inclosing ring to be applied. The inclosing ring, when slipped onto the bag or object is but a trifle larger and of such size that to slip it over the end of the object to be tied would be extremely difficult if not wholly impracticable. Thus a large amount of wire in the formation of the inclosing ring is saved.

20 There is no rapidly rotating or moving part associated with the operation of finishing the inclosing ring. The presence of such a part is dangerous to the operator and to the fabric and takes up room. There are no free projecting ends to injure the hands of the operator or the fabric. The inclosing ring when released from the forming ring surrounds the object to be tied, or the bag and if, as is usually the case, it is then necessary to tighten the inclosing ring, it can be done by twisting the loop, but this does not result in free projecting ends. An untying key is formed in the shape of a short 25 loop which leaves nothing, however, to injure either the fabric or the hands of the operator. It can be folded up tightly against the object or bag. Where inclosing rings are formed separate from the bag or 30 other object, they must be inserted over the end thereof, and must be larger than is necessary to form the closure, and hence there is a great loss of wire. In addition to this, the step in the process of making the closure, which consists in bringing the object or bag into position and then placing the inclosing finished ring thereover, is difficult and expensive. Not infrequently it is impossible, as for example, where bags are 35 being formed in a continuous series from strips of material, the bag being formed and then severed. Thus by forming the inclosing ring on the article to be tied, these and other advantages result.

40 If the inclosing ring be formed on the

object by twisting or tying its ends, the result is a rapidly moving piece of mechanism, and projecting injurious free ends. This applies to wire as distinguished from rods which might be held in position by 45 their own rigidity. Twisting or tying the wire involves also a very considerable loss.

50 The tying or twisting method has the advantage of tightening the inclosing ring on the object, as in the case of wire-tying 55 bundles of grain. Where the inclosing ring is finished by the heating processes broadly included in the term welding, or specifically by welding, they must practically in all cases be made slightly larger than the object to be tied, so as to need subsequent 60 tightening. This will usually be true because of the difficulty in drawing the wire tightly about the object in the process of forming the inclosing ring where these wires 65 are not twisted about each other. In this latter case, the twisting may be made the means of tightening. If, however, the inclosing ring is formed, for example, by welding, and is not as tight as it ought to 70 be, another step, that of separately tightening the closure, is necessary. The electrode, or other part employed in the process of forming the inclosing ring and lying within the ring, will result in making the ring 75 so large that it needs tightening.

80 The object of my invention, therefore, broadly speaking, is to avoid the objections incident to the use of rings separately made and then applied to the bag or object, and 85 the use of twisted or tied rings formed on the object. The means which I employ, broadly speaking, include the formation of a heat finished ring on the object and where necessary, its tightening by subsequent and 90 separate steps. And specifically the object 95 of my invention is to form a wire welded ring closure for bags of flexible, yielding, combustible material, and to tighten the same after they are formed on the bags so 100 as to leave an untying loop and no free, sharp ends, and the method consists in a 105 succession of steps which are necessary to bring about these results.

110 The drawings are of course very diagrammatic and a number of parts and features have been omitted, as it is believed that the operation of the machine is perfectly clear and they or their equivalents are shown in the other co-pending applications by the 115 same applicant, #601,082, filed January 6, 1911. "process for fastening bags"; #788,516, filed Sept. 8, 1913, "process of wire tying and packaging bags"; and #788,517, filed Sept. 8, 1913, "wire tie for 120 twisting bags."

125 I claim:

1. The process of wire-tying bags which consists in gathering the folds thereof together, inclosing the same with a wire, heat- 130

- joining the ends of the wire to form an inclosing ring about the bag and then tightening such ring upon the object.
2. The process of wire-tying bags which 5 consists in gathering the folds thereof together, inclosing the same with a wire, heat-joining the ends of the wire while protecting the fabric of the bag from the heat so as to form an inclosing ring about the bag, and then tightening the ring upon the bag.
3. The process of wire-tying bags which 10 consists in gathering the folds thereof together, inclosing the same with a wire, heat-joining the ends of the wire to form an inclosing ring about the bag, and then tightening the ring upon the bag.
4. The process of wire-tying bags which 15 consists in gathering the folds thereof together, inclosing the same with a wire, heat-joining the ends of the wire while protecting the fabric of the bag from the heat so as to form an inclosing ring about the bag, and then tightening the ring upon the bag by twisting an untying loop therein.
5. The process of wire-tying bags which 20 consists in gathering the folds thereof together, inclosing the same with a wire, heat-joining the ends of the wire while protecting the fabric of the bag from the heat so as to form an inclosing ring about the bag, and then tightening the ring upon the bag by twisting an untying loop therein.
6. The process of wire-tying bags which 25 consists in gathering the folds thereof together, inclosing the same with a wire bent in the form of a ring made larger than the cross section of the bag fold, heat-joining the ends of the wire to form an inclosing ring about the bag and then tightening the ring about the bag.
7. The process of wire-tying bags which 30 consists in gathering the folds thereof together, inclosing the same with a wire bent in the form of a ring made larger than the cross section of the bag fold, heat-joining the ends of the wire while protecting the fabric of the bag from the heat to form an inclosing ring about the bag.
8. The process of wire-tying bags which 35 consists in gathering the folds thereof together, inclosing the same with a wire bent in the form of a ring made larger than the cross section of the bag fold, heat-joining the ends of the wire to form an inclosing ring about the bag and then tightening the ring on the bag.
9. The process of wire-tying bags which 40 consists in gathering the folds thereof together, inclosing the same with a wire bent in the form of a ring made larger than the cross section of the bag fold, heat-joining the ends of the wire while protecting the fabric of the bag from the heat to form an inclosing ring about the bag, and then tightening the ring on the bag.
10. The process of wire-tying bags which 45 consists in gathering the folds thereof together, inclosing the same with a wire bent in the form of a ring made larger than the cross section of the bag fold, heat-joining the ends of the wire to form an inclosing ring about the bag and then tightening the ring on the bag.
11. The process of wire-tying bags which 50 consists in gathering the folds thereof together, inclosing the same with a wire bent in the form of a ring made larger than the cross section of the bag fold, heat-joining the ends of the wire while protecting the fabric of the bag from the heat to form an inclosing ring about the bag, and then tightening the ring on the bag by twisting an untying loop therein.
12. The process of wire-tying bags which 55 consists in gathering the folds thereof together, inclosing the same with a wire bent in the form of a ring but larger than the desired inclosing loop, electro-welding the ends of the wire while protecting the fabric of the bag from the heat to form an inclosing ring about the bag and then tightening the ring on the bag by twisting a loop therein.
13. The process of wire-tying bags which 60 consists in gathering the folds thereof together, inclosing the same with a wire bent and its ends overlapped, heat-joining the overlapped ends of the wire to form an inclosing ring about the bag and then tightening the ring about the bag.
14. The process of wire-tying bags which 65 consists in gathering the folds thereof together, inclosing the same with a wire bent and its ends overlapped so as to form a ring, heat-joining the ends of the wire while protecting the fabric of the bag from the heat to form an inclosing ring about the bag.
15. The process of wire-tying bags which 70 consists in gathering the folds thereof together, inclosing the same with a wire bent and its ends overlapped so as to form a ring of somewhat larger size than the cross section of the fold, heat-joining the ends of the wire to form an inclosing ring about the bag and then tightening the ring about the bag.
16. The process of wire-tying bags which 75 consists in gathering the folds thereof together, inclosing the same with a wire bent and its ends overlapped so as to form a ring, electro-welding the overlapped ends of the wire while protecting the fabric of the bag from the heat to form an inclosing ring about the bag.
17. The process of wire-tying bags which 80 consists in gathering the folds thereof together, inclosing the same with a wire bent and its ends overlapped, heat-joining the overlapped ends of the wire to form an inclosing ring about the bag.

4
closing ring about the bag, then tightening the ring on the bag by twisting an untying loop therein.

18. The process of wire-tying bags which consists in gathering the folds thereof together, inclosing the same with a wire bent and its ends overlapped so as to form a ring, heat-joining the ends of the wire while protecting the fabric of the bag from the heat to form an inclosing ring about the bag, then tightening the ring on the bag by twisting an untying loop therein.

19. The process of wire-tying bags which consists in gathering the folds thereof together, inclosing the same with a wire bent and its ends overlapped so as to form a ring of somewhat larger size than the cross section of the fold, heat-joining the ends of the

wire to form an inclosing ring about the bag, then tightening the ring on the bag by twisting an untying loop therein.

20. The process of wire-tying bags which consists in gathering the folds thereof together, inclosing the same with a wire bent and its ends overlapped so as to form a ring, electro-welding the overlapped ends of the wire while protecting the fabric of the bag from the heat to form an inclosing ring about the bag, and then tightening the ring on the bag by twisting an untying loop 30 therein.
